ARTICLE CARRYING MEANS

George Albert Lyon, Detroit, Mich.

Original application December 29, 1950, Serial No. 203,419. Divided and this application February 18, 1954, Serial No. 411,149

4 Claims. (Cl. 248—318)

The present application is a division of my copending application entitled "System for Conveying and Heat Treating Stampings," Serial No. 203,419, filed December 29, 1950, now Patent No. 2,689,578.

This invention relates to an article holding means for supporting articles during movement through work performing operations, and particularly to an article holding means for conveying cup-shaped articles through a liquid bath.

It is an object of the present invention to provide a novel article holding means for cup-shaped articles.

It is a further object of the present invention to provide novel article holding means accommodating opposite tilting of the cup-shaped article.

It is another object of the present invention to provide an economical yet rugged article holding means for securely retaining cup-shaped articles during a series of work operations thereon.

Other objects and features of this invention will more fully appear from the following detailed description taken in connection with the accompanying drawings which illustrate a single embodiment thereof and in which:

Figure 1 is a fragmentary longitudinal sectional view illustrating the work carrying means of the present invention as it would be employed in moving a cup-shaped article from one station through a heat treating bath to an adjoining station, with certain of the work supports broken away so as to more clearly illustrate the remaining supports;

Figure 2 is a fragmentary longitudinal sectional view similar to Figure 1 but taken at the discharge end of the heat treating bath;

Figure 3 is a cross-sectional view taken on substantially the line III—III of Figure 1 through the salt bath furnace and showing the relation of the conveying means thereto;

Figure 4 is a plan view, partly in section, taken on the line IV—IV of Figure 1 looking downwardly and showing how the support diagonally carries the cup-shaped article; and

Figure 5 is a fragmentary sectional view taken on substantially the line V—V of Figure 4 looking in the direction indicated by the arrows and illustrating how the article is engaged by the support.

The reference numeral 12 designates a conveyor for transferring articles from one station through a heated fused salt bath 14 to a second station. The conveyor 12 includes an I-beam track 19 of an I cross-section from which is suspended a plurality of spaced article supports or hangers 20. The hangers are all identical in construction so that a description of one will suffice for all. Each of these article supports includes a vertical bar 21 having secured to its upper end a yoke 22, the spaced arms of which (Fig. 3) carry spaced aligned rolls 23—23 adapted to roll along and on the lower flange of the track 19.

The lower end of the bar 21 (Figs. 4 and 5) has suitably secured to it a pair of divergent rod-like arms

2

24—25 for detachably receiving and carrying the cup-shaped article or cartridge casing C. The arm 24 has a turned extremity 26 engaging over and inside of the outer edge of the casing at its open end. The other arm 25 has its lower end formed into an eye 27 through which the cartridge casing extends; the casing resting on the lower portion of the eye. The bottom of the eye 27 has a longitudinal arm 28 with a turned extremity 29 adapted to engage and abut the outer surface of the bottom of the casing C.

It will be noted from Figures 4 and 5 that the arms 24 and 25 are connected to the bar 21 at such an angle as to carry the casing in a diagonal position with reference to the direction of movement or direction of the track or rail 19. This arrangement enables the articles to be positioned in closed parallel relation and also facilitates the filling and emptying of the casings.

The support or hanger bars 21 are rigid throughout their entire extent and are all connected adjacent their upper ends in spaced vertically articulated relation for movement together along the track 19 by a series of non-buckling links 30 which are of a construction co-operable with any conventional drive means such as sprockets or the like (not shown). To this end, the hanger bars 21 have rigid with the upper end portions thereof forwardly and rearwardly directed cross-arm structure 30a to which the links 30 are respectively pivotally connected about vertical axes. Thereby the bars 20 are enabled to move about the transverse turns in the conveyor 12 but are held against free pivoting about a transverse or horizontal axis.

Also it will be perceived from Figures 1 and 2 that the track or rail 19 is so curved that it descends downwardly toward the inlet of the fused salt bath 14 (Fig. 1) and ascends at the outlet end (Fig. 2) of the bath. In other words, the track has an intermediate downward bend over the top of the fused salt bath 14. By virtue of the non-buckling character of the links 30 and the manner in which the rigid bars 21 are controlled by the links, the major lower end portions of the bars below the links will swing rearwardly as the bars move down the curved descending portion of the track 19, whereby to tilt upwardly the open ends of the casings C supported thereby, while at the ascending portion of the track the bars 20 swing forwardly and thereby move the casings C toward an upended position.

This arrangement is such that the articles enter the bath bottom first and must likewise ascend out of the bath bottom first. This feature, together with the diagonal positioning of each of the articles, enables a proper filling and emptying of the articles with heated liquid as they traverse the length of the bath. It is very desirable that each article be completely emptied of any of the bath liquid so as to minimize the likelihood of the adherence of any of the salts thereto.

The fused salt bath 14 may be of any suitable construction and include a central container 35 for the liquid, a refractory lining 31 and an outer brick or ceramic material 32. The bath 33 may be made up of any suitable fused salts such, for example, as that disclosed in my own issued Patent No. 2,059,468.

Any suitable means may be employed for heating up the fused salts to maintain the same in heated liquid form suitable for the heat conditioning desired. The extent to which the bath is heated depends upon the character of the steel being treated, although, for illustration, excellent results may be attained by maintaining the bath at a temperature of about 1250° F.

The time during which the casings are in the bath depends upon the size of the casing and the character of the steel, although it should only require a few minutes

to effect the conditioning as "distinguished from hours now used in a heated atmosphere type furnace.

Referring to Figures 4 and 5 in more detail, it will be observed that the article carrying means of the present invention comprises a flat hanger bar 21, a first rod-like arm 24 having a rearwardly and downwardly extending portion terminating in an inturned extremity 26 adapted for engaging in the open end of a cup-shaped article and having an oblique opposite end portion 40 secured to the broad face of the bar 21, the downwardly extending portion of the arm 24 extending obliquely to the plane of the bar. The article holding means also includes a second rod-like arm 25 secured to the broad face of the bar 21 at an obliquely extending end portion 42 and formed into an eye 27 through which the cup-shaped article is adapted to extend, the eye having a longitudinal member 28 with a turned extremity 29 adapted to abut the closed end of the article carried at its open end by the first arm. By this means, the horizontal orientation of the article is effectively controlled, the lower portion 43 of the arm 24 cooperating with the inturned extremity 26 to retain the open end of the article against vertical movement and the eye 27 substantially retaining the closed end of the article against vertical movement, while the portion 44 of the arm 24 prevents movement of the article in one axial direction and the turned extremity 29 prevents movement of the article in the other axial direction.

As seen in Figures 1, 2, 3 and 6, the eye 27 is of a somewhat larger diameter than the article C so that the open end of the article can be inserted through the eye 27 and into engagement with the turned extremity 26 while the closed end is then lowered into engagement with the turned extremity 29. Alternatively, of course, the closed end may be inserted through the eye 27 in the opposite direction riding over the turned extremity 29 to allow the open end of the article to be engaged with the turned extremity 26.

It will be understood that modifications and variations may be effected without departing from the scope of the novel concepts of the present invention.

I claim as my invention:

1. Article support means comprising a flat hanger bar, a first rod-like arm having a rearwardly and downwardly extending portion terminating in an inturned extremity for engaging the interior wall portion of an open ended cylindrical article to support the article at one end against downward movement and against axial movement in one direction while leaving the open end substantially unobstructed, said first rod-like arm having an opposite end portion secured to said bar, and a second rod-like arm secured at one end to said bar and formed into an eye through which the article is adapted to extend, the eye having a rigid longitudinal member extending therefrom in the direction opposite from the position of the inturned extremity of said first rod-like arm and having a turned-up extremity adapted to abut the other end of the article when said article is resting in said eye and on said inturned extremity, thereby preventing axial movement of the article in either direction.

2. Article support means comprising a first arm having a lateral projection for engaging within an opening in one end of a cylindrical article, and a second arm rigidly interconnected with said first arm and provided with an eye portion through which said article is adapted to extend in supported relation, the eye portion having an extension thereon extending generally longitudinally in a direction away from said first arm, said last named extension having an upwardly extending projection fixed

thereto for abutting the other end of the article, said eye being of larger cross-section than said article and the upward projection on said longitudinal extension being of relatively small upward extent whereby said eye and upward projection accommodate insertion of the article through the eye and over the upward projection to permit engagement of the said one end of the article with said first arm and accommodate axial confinement of the article between the first arm and said projection after engagement of the one end with the first arm to thereby prevent horizontal movement of the article relative to the said arms.

3. A hanger for a cup-shaped article of generally constant external diameter having an open end and a closed end, comprising a first arm having an extremity of cross-section small in comparison with the interior cross-section of the article and engaging an interior wall portion of the article at the open end thereof when the article is placed in generally horizontal position, and a second arm carried with said first arm and encircling at least a major portion of said article adjacent the closed end thereof and of rigid non-expansible construction to limit lateral or vertical movement of the article within the second arm, the second arm having a longitudinally extending member rigidly secured to the encircling portion thereof and having a short upward projection abutting the closed end of the article to prevent axial displacement of the article out of engagement with the extremity of said first arm, and means connected to said first and second arms for rigidly interconnecting and supporting said arms, the encircling of said second arm being sufficiently free to permit vertically upward movement of said article to a position above said short upward projection to permit axial disengagement of said article from the said extremity and from the hanger.

4. In combination with a hanger bar, means for supporting a cylindrical article having an open end in a fixed relation to said hanger bar comprising, a first arm secured to said hanger bar and extending across one wall of said article and turned into the open end of said article for supporting the article against axial movement in one direction and against downward movement of said open end, a second arm secured to said hanger bar and having portions extending horizontally and vertically for supporting the article adjacent the other end thereof against lateral and downward movement, a third arm secured to said second arm and extending laterally away from said first arm and having an upwardly extending portion for engaging the other end of the article to retain the article against axial displacement in the other direction without impeding upward movement of the article to a position above said upwardly extending portion of the third arm to thereby permit disengagement of the article therefrom to permit axial movement of the article away from said first arm and thereby permit generally axial removal of said article from said supporting means.
